UNITED STATES PATENT OFFICE

GEORGE HEYL, OF NEWARK, NEW JERSEY.

IMPROVEMENT IN EXTENSION-TABLES.

Specification forming part of Letters Patent No. **170,369**, dated November 23, 1875; application filed September 8, 1875.

To all whom it may concern:

Be it known that I, GEORGE HEYL, of the city of Newark, in the county of Essex and State of New Jersey, have invented certain new and useful Improvements in Extension-Tables; and I do hereby declare that the following is a full, clear, and exact description thereof, which will enable others skilled in the art to which it pertains to make and use the same, reference being had to the accompanying drawing, and to the letters of reference marked thereon, which form a part of this specification.

The object of my invention is to provide a means for storing the extra leaves of an extension-table without resorting to the usual unsightly racks or to the expensive appliances heretofore employed; and this I accomplish in the manner shown in the accompanying drawing, in which—

Figure 1 is a sectional elevation of an extension-table, showing my improvement; and Fig. 2, a perspective view of one of the detachable leaves.

The table consists, as usual, of two sections, in each of which two legs, G G, a cross-piece, E, and brackets F F support one section of the permanent top. The slides B B C C' C' are constructed in the ordinary manner, the slides C' C' being secured permanently to one section of the table, and the slides B B to the opposite section. At the inner sides of the slides B are ribs or flanges a', for a purpose described hereafter.

Each of the extra detachable leaves of the table is divided in the center, and the two parts are connected by hinges a, so that the

leaf may be unfolded and placed upon the table in the usual position, Fig. 1, or may be folded and stored within the frame of the table, resting upon the flanges a, as shown in dotted lines.

Heretofore it has been usual either to store the extra leaves in racks or else to provide a receptacle within the frame of the table, and whenever the latter mode has been adopted the receptacle has been placed in a central position, connected with the movable slides C.

This arrangement necessitates the use of an additional leg for supporting the receptacle, the movable slides not possessing sufficient strength in themselves to maintain the increased weight. The additional leg not only increases the cost of the table, but is a constant source of annoyance, owing to the difficulty of bracing it so that it will not give way when the table is moved. All these objections are obviated by forming a receptacle within the permanent slides B B, which, being secured to and firmly supported by the stationary frame, will easily sustain any weight which they may be required to support.

I claim—

An extension-table in which flanges a a' are arranged upon the permanent slides B, to support the folded extra leaves, all as set forth.

In testimony that I claim the foregoing as my own invention I affix hereto my signature in presence of two witnesses.

GEORGE HEYL.
